PICK UP TOOL

Raymond B. Nockleby, Rte. 1, Kalispell, Mont. 59901

Filed Oct. 15, 1973, Ser. No. 406,376

Term of patent 14 years

Int. Cl. D8—05

U.S. Cl. D8—52

FIG. 4

FIG. 1

FIG. 5

FIG. 1 is a side elevation view of the pick up tool, the opposite side being a mirror image;

FIG. 2 is an end view looking at the top of FIG. 1;

FIG. 3 is an end view looking at the bottom of FIG. 1;

FIG. 4 is an elevation view from the left in FIG. 1; and

FIG. 5 is an elevation view from the right in FIG. 1.

I claim:

The ornamental design for a pick up tool, as shown and described.
